UNITED STATES PATENT OFFICE

155,775

DESIGN FOR AN INK RESERVOIR DESK STAND

Warren R. Burns, Newton, Mass., assignor to The
Carter's Ink Company, Cambridge, Mass., a cor-
poration of Massachusetts

Application August 13, 1948, Serial No. 148,100

Term of patent 7 years

(Cl. D74—8)

To all whom it may concern:

Be it known that I, Warren R. Burns, a citizen of the United States, and resident of Newton, in the county of Middlesex, State of Massachusetts, have invented a new, original, and ornamental Design for an Ink Reservoir Desk Stand, of which the following is a specification, reference being had to the accompanying drawing, forming part thereof.

Fig. 1 is a perspective view of an ink reservoir desk stand, showing my new design; and

Fig. 2 is a side elevation thereof.

I claim:

The ornamental design for an ink reservoir desk stand, substantially as shown.

WARREN R. BURNS.
